CLAIM

The ornamental design for a dental flosser, as shown and described.

DESCRIPTION

FIG. 1 is a left side perspective view of dental flosser showing the new design, the left and right sides being mirror images of one another;

FIG. 2 is a left side elevational view of the dental flosser of FIG. 1;

FIG. 3 is a top view of the dental flosser of FIG. 1;

FIG. 4. is a bottom view of the dental flosser of FIG. 1;

FIG. 5 is rear view of the dental flosser of FIG. 1; and,

FIG. 6 is a front view of the dental flosser of FIG. 1.

The broken lines in the drawing are for illustrative purposes only and form no part of the claimed design.
